METHOD FOR PRODUCING THERAPEUTIC RAYS

Application filed May 28, 1925. Serial No. 33,446.

The present invention relates to therapeutic apparatus, and more particularly to therapeutic apparatus and methods employing the curative properties of rays of the invisible spectrum.

The therapeutic and bactericidal characteristics of ultra violet light have been known for some time, but their use in the cure of diseases has been attended with considerable difficulty, particularly because of the presence of the shorter rays of the invisible spectrum which are produced by the usual existing sources of ultra violet light. The usual apparatus for producing the actinic rays is a quartz mercury vapor lamp which is quite rich, not only in the valuable curative rays but also in the more caustic shorter emanations. It is from these latter that the principal difficulties attending the use of ultra violet light as a medical agency arise, because they exhibit a marked caustic and destructive effect on human tissue, often resulting in grave dermatitis under continued exposure to the rays. It has been found that emanations of less than 300 milli-microns in wave length require extreme care in application to the body. It will be seen that treatment with the mercury arc, whose spectrum extends well into the extreme ultra violet region, usually corresponding to wave lengths of about 210 milli-microns, should be attempted only by skilled technicians and even then for only short periods of time. In some cases screens or selective filters which are opaque to the shorter rays have been used in connection with the mercury arc to permit safe operation under more continued exposure, but the fact remains that such devices are not available for use by the layman, and for this reason phototherapeutic treatment is apt to be inconvenient and is always expensive for the patient.

The object of the present invention is to provide a method and apparatus by which the therapeutic rays of the invisible spectrum

may be inexpensively and conveniently obtained and safely applied to any part of the human body even by those unskilled in medical technique.

I have discovered that a solid body of a material which becomes incandescent at a high temperature, such as tungsten, while emitting only rays of the visible spectrum at normal operating temperature, will at increased temperatures emanate actinic rays extending sufficiently into the ultra violet region to possess marked curative properties, the wave length band including more of the shorter rays as the temperature increases. A low voltage electric lamp having a tungsten filament is well suited for this purpose, and for safe and effective use is preferably operated at about 10% in excess of normal voltage to give rays which extend from a lower limit of about 300 milli-microns in wave length. The bulb of the lamp is preferably of a material which is transparent to such longer wave lengths, but opaque to the shorter caustic rays. The rays are directed and concentrated upon an affected area of the body by suitable reflecting, refracting and conducting means.

In the accompanying drawings illustrating the preferred form of the invention, Fig. 1 is an elevation partly in section of the improved therapeutic apparatus; and Fig. 2 is a side view of a modified form of applicator.

The embodiment of the invention illustrated in the drawings comprises an aluminum casing 4 provided with a removable cover 6. The casing has a circular boss 8 to receive a lamp socket 10, which can be adjusted vertically and there secured by the set screw 11. A low voltage incandescent lamp 12 having a concentrated tungsten filament 14 is mounted in the socket 10. The filament is energized from a suitable alternating or direct current source through conductors 16 extending through a handle 18 secured to the bottom of the casing. The bulb

preferably has a filament designed normally to run on 6 to 8 volts, the ordinary automobile headlight bulb serving admirably for this use, and the electrical connections with the filament conveniently include a transformer for stepping down the voltage if an alternating current source is used, or a series resistance if a direct current source is used. The voltage applied to the filament is preferably about 10% in excess of normal voltage; for an 8-volt bulb the voltage applied to the filament would be approximately 9 volts.

Received in a boss 20 in the side of the casing and secured by a set screw 22 is an applicator 24 which consists of material conductive to the rays emanated from the lamp and which is in direct contact with the wall of the bulb, as shown in Fig. 1. The applicator 24 is preferably of quartz which, as is well known, is not only remarkably transparent to the rays of the invisible as well as the visible spectrum, but also serves to conduct the rays and direct them toward any desired point. This part, however, may with good effect be made of borosilicate glass, commonly known under the trade name of "pyrex", which has been found to be a good conductor of the emitted rays, or even an aqueous solution of alum or copper sulphate in a sealed tube may be employed for the applicator. The glass bulb 12 is preferably of the ordinary soda-lead or soda-lime construction which, as has been found, does not greatly diminish the volume or curative value of the rays and is advantageous because of its ability to screen any of the deleterious rays of shorter wave length. A borosilicate glass bulb may also safely be used.

In order to provide for maximum effective use of the rays emitted from the filament, an aluminum reflector 26 is mounted in back of the bulb by means of a supporting rod 28 received in a column 30 secured to the bottom of the casing and adapted to permit adjustment of the reflector through the use of a thumbscrew 32. The reflector is adjusted so as to cause the rays from the filament to impinge directly upon the inner end of the applicator 24 which then conducts the rays to the desired point of application.

In operation, after the socket 10 has been vertically adjusted to bring the filament in line with the applicator 24, and the reflector 26 has been brought to the proper distance behind the bulb, the current is applied and the filament is heated by an approximately 10% excess voltage. The applicator is directed toward an affected part of the body, either to an exposed area or through one of the orifices of the body, such as the mouth to treat diseased tonsils, or the nasal passages to treat acute coryza.

It has been found that contact of the sides of the applicator against a moist part of the

body, as in the case of tonsil treatment, causes a dispersion of the rays through the sides of the applicator, thus decreasing from their value at its end. To prevent such action, the applicator may be provided with a shield indicated at 34, which is of metal and is received upon the boss 20 of the casing and secured thereto by a screw 36. The shield is spaced slightly away from the applicator and at its end has a downturned lip 38 which engages with the sides of the applicator to afford a smooth surface which can in no way cause injury to the patient. The use of such a shield does not detract from the direct conduction of rays through the applicator and hence permits use of the apparatus where the sides of the applicator would normally contact with moist parts of the body.

In some cases it is desirable to provide for a marked dispersing effect, and to this end the applicator may be provided with a series of indentations or flat facets which cause a prismatic dispersion of the rays in the form of a series of isolated pencils emerging from the several facets. This construction is illustrated in Fig. 2 showing a number of indentations or notches 40 in the end of the applicator.

The applicator 42, which is illustrated in Fig. 2, is of curved shape and is preferably formed of quartz, which is known to possess the peculiar property of conducting rays of light through substantially any desired angle and permitting them to issue in a concentrated pencil at the end of the rod. An applicator of the form illustrated in Fig. 2 with or without the indentations 40 would be useful, for instance, in the application of ultra violet rays to different parts of the mouth which might not afford convenient access for the straight form of applicator shown in Fig. 1.

The present invention when operated according to the method above described affords an excellent source of ultra violet light in sufficient volume to possess decided therapeutic properties without the presence of rays of shorter wave length which would have a considerably cellular caustic action. The apparatus is inexpensive and may be used even by unskilled persons for extended periods of time and without danger of destruction of the tissues of the body such as would occur from exposure to the rays of the mercury vapor arc.

Having thus described the invention, what is claimed is:

1. A method of producing therapeutic rays which consists in heating an incandescent tungsten filament lamp having a glass envelope to a temperature to emit a continuous spectrum of visible and ultra-violet light extending to wave lengths of 300 milli-microns and below, and filtering the rays through the

glass envelope to cut off shorter caustic rays of wave lengths substantially shorter than 300 milli-microns.

2. A method of producing therapeutic rays which consists in heating an incandescent tungsten filament lamp having a soda-lime glass envelope to a temperature to emit a continuous spectrum of visible and ultra-violet light extending to wave lengths of 300 milli-microns and below, and filtering the rays through the soda lime glass envelope to cut off shorter caustic rays of wave lengths substantially shorter than 300 milli-microns.

10 In testimony whereof I have signed my name to this specification.

15 EDWARD W. BOERSTLER.
